(57) CLAIM

The ornamental design for a bannister-mantel clip for supporting holiday ornamental-decorative elements, as shown.

DESCRIPTION

FIG. 2 is a perspective view of the bannister-mantel clip for supporting holiday ornamental-decorative elements showing a bottom, a rear and a left side of my new design;
FIG. 3 is the bannister-mantel clip for supporting holiday ornamental-decorative elements showing the front view thereof;

FIG. 4 is the bannister-mantel clip for supporting holiday ornamental-decorative elements showing the rear view thereof;

FIG. 5 is the bannister-mantel clip for supporting holiday ornamental-decorative elements showing the right-side view thereof;

FIG. 6 is the bannister-mantel clip for supporting holiday ornamental-decorative elements showing the left-side view thereof;

FIG. 7 is the bannister-mantel clip for supporting holiday ornamental-decorative elements showing the top view thereof; and,

FIG. 8 is the bannister-mantel clip for supporting holiday ornamental-decorative elements showing the bottom view thereof.
